(57) **CLAIM**

The ornamental design for a receiver for a gun, as shown and described.

DESCRIPTION

FIG. 1 is a front-upper-left isometric view of a receiver for a gun showing our new design comprising an assembly of a first and second component shown for the purposes of illustration; FIG. 2 is a rear-lower-right isometric view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is a front-upper-left isometric view of the first component thereof shown separately for purposes of illustration; FIG. 10 is a rear-lower-right isometric view thereof;

FIG. 11 is a front view thereof;

FIG. 12 is a back view thereof;

FIG. 13 is a left view thereof;

FIG. 14 is a right view thereof;

FIG. 15 is a top view thereof;

FIG. 16 is a bottom view thereof;

FIG. 17 is a front-upper-left isometric view of the second component thereof shown separately for purposes of illustration;

FIG. 18 is a rear-lower-right isometric view thereof;

FIG. 19 is a front view thereof;

FIG. 20 is a back view thereof;

FIG. 21 is a left view thereof;

FIG. 22 is a right view thereof;

FIG. 23 is a top view thereof; and,

FIG. 24 is a bottom view thereof.

The dotted lines are shown for purposes of illustration and form no part of the claimed design.

1 Claim, 12 Drawing Sheets
